UNITED STATES PATENT OFFICE.

BENJAMIN F. ZIMMERMAN, OF WASHINGTON, DISTRICT OF COLUMBIA.

VACUUM FUEL-FEED APPARATUS.

1,366,760.

Specification of Letters Patent. Patented Jan. 25, 1921.

Application filed March 23, 1920. Serial No. 368,163.

To all whom it may concern:

Be it known that I, BENJAMIN F. ZIMMERMAN, a citizen of the United States, residing at Washington, in the District of Columbia, have invented certain new and useful Improvements in Vacuum Fuel-Feed Apparatus, of which the following is a specification.

This invention relates to certain new and useful improvements in vacuum fuel feed systems, and a leading object of the invention is to provide a new and improved means for filtering the liquid fuel that passes from the main supply tank to the vacuum system, thus further purifying the fuel before it is delivered to the vacuum tank of the system.

A further object of the present invention is to construct the filtering means in the form of a sight-feed; that is, to appropriately position in the gasoline- or liquid-fuel feed-line a receptacle of a transparent character, or having a transparent portion which serves as a visual indicator and permits the operator of the vehicle supplied with a vacuum fuel feed system provided with my invention, to ascertain at any time by the physical condition of the fuel being sucked through the feed line, if the vacuum system is properly functioning.

My invention is in the nature of an accessory for gasoline or other cars employing a liquid-fuel since it can be readily attached to the usual vacuum tank, of such systems, the said device serving the two-fold purpose of a separator of sedimentary matter carried in the liquid fuel, and as a visual indicator of the working conditions of the system.

With the foregoing and other objects in view, my invention consists of the parts, and the constructions, arrangements and combinations of parts which I will hereinafter describe and point out in the appended claims.

In the accompanying drawing forming part of this specification and in which similar reference characters indicate like parts in the several views;

Figure 1 is a side elevation, more or less diagrammatic, showing a well known arrangement of a vacuum fuel feed in its association with the engine of an automobile, and showing a preferred location of my invention in the gasoline feed line of said system.

Fig. 2 is an enlarged vertical sectional

view of my combined separator and sight feed device.

As is well known to those familiar with the vacuum fuel feed systems commonly employed in connection with the internal combustion engines of automobiles, a pipe, 2, leads from the main storage tank, 3, to the vacuum chamber or receiving chamber of the vacuum fuel feed tank, 4, which tank is usually positioned near the engine and is sufficiently elevated to cause the liquid fuel to be fed therefrom by gravity to the usual carburetor. This type of system and the various specific parts thereof are well known and form no essential part of my invention and therefore they are not herein illustrated in detail.

In my invention, I let into the pipe line, 2, leading from the main supply tank to the vacuum tank, 4, my improved separator and sight-feed appliance. This device consists, substantially, of upper and lower recessed heads, *a*, *b*, made of some appropriate material, as metal, and an intermediate cylinder or tube, *A*, of glass or other transparent substance, or of some material having a transparent sight opening of sufficient area to permit the contents of the cylinder or tube to be viewed.

The annular recessing of the inner faces of the heads enables the ends of the glass cylinder to be snugly seated therein and against appropriate packings, *c*, to form leak-tight joints against which the ends of the cylinder are clamped by the screw rods, *d*, which pass through the marginal portions of the heads and are secured by appropriate nuts, *e*.

The lower head, *a*, is pierced at *f* to admit the threaded nipple *g* of a coupling member, *h*, which is appropriately fitted to the fuel feed line 2; the nipple, *g*, also carries a tube or hollow extension, *i*, which extends for a substantial distance into the chamber formed by the glass cylinder, said tube having its upper portion cut-away on one side and the top of the tube bent over to constitute a deflecting lip, *i'*, and to form substantially a spraying nozzle whose discharge is substantially transverse of the axis of the cylinder, said nozzle being designed to deliver the flowing liquid fuel laterally or across the cylinder and into the body of gasoline contained in the cylinder; this produces agitation and gives a foamy appear-

ance to the body of gasoline and this condition serves to indicate if the vacuum function of the system is being properly performed.

5 The upper head, *b*, of my device carries within its recessed portion a fine-mesh screen, *k*, or filtering agent of suitable character; as shown, this screen practically closes the upper end of the glass cylinder, appropriate 10 packed joints being provided to insure against leakage or the admission of atmospheric air, and through said screen the gasoline or other liquid fuel is compelled to pass in order to reach the suction tube or pipe, *l*, 15 leading to the usual vacuum chamber of tank 4, of the system.

The lower head, *a*, is also provided with a removable clean-out plug, *m*, for the delivery of sedimentary matter which is separated 20 from the liquid in the cylinder.

From the foregoing it will be understood that this invention has been devised for a two-fold purpose; namely, to additionally filter the gasoline, or liquid fuel, that passes 25 from the main supply tank to the vacuum system, and to visibly indicate if the system is properly functioning.

The systems mentioned have delicate parts, say for instance the usual float and 30 valves and particularly the so-called flap-valve past which the gasoline flows from the vacuum chamber to the usual gravity compartment of the tank 4. Often small particles of grit or foreign matter with 35 which the gasoline is charged lodged under the said flap valve and prevent its full closing thereby impairing the successful operation of the valve and the efficiency of the system of which it is a part. By screening 40 out the objectionable sedimentary matter before the gasoline enters the vacuum tank, the above noted objection is overcome.

Again, in such systems as I have mentioned, the usual float sometimes sticks on 45 one of the valves actuated by the float and ceases to properly function, with the result that gasoline is permitted to pass the valve and continuously flow to the intake manifold of the engine, thus permitting the gasoline 50 to mix with the lubricant. This action would greatly impair if not substantially destroy the function of the lubricating oil and, also, more or less prevent effective carburation.

55 Under the present vacuum fuel systems, so far as I am advised, no visible or signaling means are provided to make manifest an improper functioning of the apparatus and hence the presence of such difficulties as I 60 have mentioned, is not readily apparent and excessive repair bills arising from the experimentation to ascertain the source of trouble often result. With my invention, however, if the system sticks, or a valve does 65 not properly seat or from any other cause a

substantially perfect vacuum is not maintained and the system fails to cycle properly, this condition is made apparent by lowering of the liquid level in the sight tube or cylinder; when the system is functioning 70 properly the gasoline which is being drawn into the tank, 4, fills the transparent cylinder and fresh accretions are discharged laterally into the body of gasoline in the cylinder and agitate the same and the air entrained in 75 this gasoline causes small bubbles to appear in the body of the gasoline in the cylinder, the presence of these bubbles being readily visible. This condition maintains until the 80 vacuum is broken, when the level of the liquid in the cylinder falls to that of the supply nozzle. There is always, however, a body of quiescent gasoline in the transparent cylinder or below the level of the nozzle and this body of liquid serves as a settling 85 zone for sedimentary matter, which may be removed when desired by removing the clean out plug, or opening an equivalent part.

The device described is composed of few 90 parts and may be readily attached to the existing vacuum fuel feed systems without any substantial disarrangement of the parts thereof.

Having thus described my invention what I claim as new and desire to secure by Letters Patent is:—

1. In a vacuum fuel feed system, the combination with a vacuum tank and a liquid fuel supply, of a receiver in the fuel supply line leading to the tank, said receiver adapted to be maintained substantially full of fuel during the existence of the vacuum in the tank, and having a transparent portion, and an internal nozzle fixed to the bottom of the receiver and having its upper end adapted to discharge into the column of fuel in the receiver at an angle to the axis of said receiver.

2. In a vacuum fuel feed system, the combination with a vacuum tank and a liquid fuel feed supply, of a receiver let into the fuel supply line leading to the tank, said receiver having a transparent portion and having means fixed to and extending above its bottom adapted to deliver the incoming fuel substantially across the axis of the receiver and directly into the column of fuel in the receiver and by agitation of said fuel visually indicate the condition of the working of vacuum tank.

3. A vacuum fuel feed system having a main fuel supply and a vacuum tank connected thereto, said system having, also, a transparent fuel receiver let into the feed line between the supply and the tank and adapted to be maintained substantially full of fuel by the working vacuum in the system, said receiver provided with means for admitting the fresh accretions of the fuel into the fuel column in substantially a lat-

eral direction at a point above its bottom, said means determining the depth of a body of substantially quiescent fuel to be retained in the lower portion of the receiver.

- 5 4. In a vacuum fuel feed system, the combination with a vacuum tank and a liquid fuel supply, of a receiver in the fuel supply line leading to the tank, said receiver having a deflecting nozzle in its interior above 10 the bottom thereof and forming a part of said supply line, and said receiver having an outlet in its upper portion also forming a part of said supply line.

- 5 5. In a vacuum fuel feed system, the combination with a vacuum tank and a liquid fuel supply, of a receiver in the fuel supply line leading to the tank, said receiver adapted to be maintained substantially full of fuel by the working vacuum in the system 20 and said receiver having a deflecting nozzle in its interior fixed to and extending above the bottom thereof and forming a part of said supply line, said receiver having an outlet in its upper portion also forming a 25 part of said supply line, and a filtering medium in the upper portion of the receiver and through which the fuel must pass to reach said outlet.

6. A combined filtering and visual indicating device for a vacuum fuel feed system,

said device consisting of upper and lower heads and an intermediate transparent tubular member, means for connecting said heads and clamping the latter against the ends of said member, a fuel inlet pipe entering the 35 bottom of the lower head and extending a substantial distance into the tubular member, said pipe having a deflecting nozzle formation on its upper end adapted to deliver fresh accretions of fuel into the column 40 of fuel in the receiver, a coupling member on the lower end of said pipe, a filter agent on the upper portion of the tubular member, and a pipe in the upper head connecting with the space above said filter agent. 45

7. The method herein described of indicating the working conditions of a vacuum fuel-feed system, said method consisting, essentially, in introducing into the fuel-feed line of the system so as to subject to the 50 vacuum thereof, a visible fuel container into which accretions of the flowing fuel are admitted in such manner as to produce visible agitation of the fuel contents of said container while the system is properly functioning, the agitation ceasing and the fuel level in the container visibly lowering when there occurs an interruption of the vacuum. 55

In testimony whereof I affix my signature.
BENJAMIN F. ZIMMERMAN.
